UNITED STATES PATENT OFFICE.

EMIL ZULLIG, OF WEEHAWKEN, NEW JERSEY.

DESIGN FOR FILET LACE.

51,803.

Specification for Design.

Patented Feb. 19, 1918.

Application filed December 10, 1917. Serial No. 206,563. Term of patent 3½ years.

To all whom it may concern:

Be it known that I, EMIL ZULLIG, a citizen of the Republic of Switzerland, residing at 208 Dodd street, Weehawken, county of Hudson, and State of New Jersey, have invented a new, original, and ornamental Design for Filet Lace, of which the following is a specification, reference being had to the accompanying drawing, forming part thereof.

The figure is a plan view of a piece of filet lace showing my new design.

I claim,

The ornamental design for filet lace as shown.

EMIL ZULLIG.
